W. J. SPENCE

PORTABLE LAMP

Filed May 15, 1922

Inventor:
William J. Spence
by James R. Hodder
Attest.

UNITED STATES PATENT OFFICE.

WILLIAM J. SPENCE, OF LYNN, MASSACHUSETTS.

PORTABLE LAMP.

Application filed May 15, 1922. Serial No. 561,076.

To all whom it may concern:

Be it known that I, WILLIAM J. SPENCE, a subject of the King of Great Britain, and a resident of Lynn, Massachusetts, have invented an Improvement in Portable Lamps, of which the following description, in connection with the accompanying drawings, is a specification, like letters on the drawings representing like parts.

10 My present invention relates to lighting fixtures and more particularly to a portable lighting fixture or lamp base of the type ordinarily known as desk or reading lamps.

In the construction of this particular 15 class of device, difficulty has been experienced in so devising the swivel portions that the same may be readily adjusted with a minimum effort and have the parts remain in their adjusted position. I have obviated

20 the objectionable features of prior devices of this character and have devised a swivel joint for the lower end of the goose-neck which is relatively free to move for the purpose of adjusting the goose-neck, and in any 25 adjusted position, will remain there without danger of accidental displacement. Again, I have arranged the goose-neck to be constructed of relatively light commercial hollow tubing and have formed a socket or lamp 30 holding end integral with the goose-neck itself, this construction reducing the number of parts heretofore deemed necessary in this class of apparatus and the resultant structure is simple in character, neat in ap- 35

pearance, and efficient in operation. My improved form of swivel joint for use in attaching the lower end of the goose-neck to the base proper of the device is arranged to hold the goose-neck in position under a con- 40

stant spring tension and this tension may be adjusted as desired, and when once adjusted, will remain in this condition indefinitely. I find it possible to adjust the tension of this portion of the apparatus during the process of manufacture and therefore provide 45 no means, readily accessible to the user, for adjusting the tension of the joint after it leaves the factory, it having been found that the constant adjustment of this joint by the

50 user in prior devices resulted in rapid deterioration of the device. Such continual adjustment was necessary in prior apparatus because of the defective form of swivel device employed.

55 The particular object of my invention,

therefore, is an improved form of portable lamp base.

Another object is an improved form of 60 swivel joint applicable for use in devices of this character.

Other objects and novel features of the construction and arrangement of parts of the device constituting my invention will appear as the description of the invention progresses.

65 In the accompanying drawings illustrating the preferred embodiment of my invention:

Fig. 1 is a side elevation;

Fig. 2 is a plan view;

Fig. 3 is a section on the line 3—3 of Fig. 70 2;

Fig. 4 is a section on the line 4—4 of Fig. 75 1; and

Fig. 5 is a section on the line 5—5 of Fig. 1, but showing a slightly modified form of 75 swivel joint.

Referring to the drawings, 10 designates a base of any suitable size and contour having upwardly extending therefrom lugs 11 80 and 12 spaced apart from each other a suitable distance to receive the lower end of a goose-neck 14, and said base and lugs may be of any suitable metal or material and may be as plain or ornamental as may be desired. Each lug 11 and 12 is provided with a hole 13, these holes being of any suitable size and are in alinement with each other, the axes of the holes being horizontal. Fitting within each hole 13 is a cylindrical member 15 of a width equal to the width of the lugs 11 and 12 and prevented from rotation in the holes 13 by pins 35. This cylindrical member is provided with a plurality of slots 85 of saw cuts 16 on either side thereof and these slots or saw cuts extend a substantial distance beyond the center of such member. These members 15 are drilled to receive a rod 17 threaded at each end to receive collars 18 and these collars are provided with 90 holes or depressions 19 to receive a spanner for adjusting purposes.

The goose-neck 14 is preferably formed of 95 commercial square brass tubing and may be of any conventional form, the upper end being cut away on diametrically opposite faces to form ends 20, as shown in Fig. 2, and these ends form a fork to the extreme ends of which are pivotally mounted a yoke 21, 100 this pivotal mounting being comprised of a 105 110

rivet 22 on one side and a threaded screw 23 on the other side, this threaded screw being provided with a wing nut 24 and by means of which the yoke 21 may be secured at any desired adjusted position. Mounted on the yoke 21 is a nipple 25 to which a lamp socket or other suitable light support fixture may be attached, this light holding member being adapted to receive a lamp bulb 27 and 10 a shade 28. A lamp cord 36 from socket 26 passes through the hollow goose-neck 14 and out through an orifice (bracket not shown) near the bottom where it may be provided with the usual plug for attachment 15 to a source of current.

It will be obvious from the above that the collars 18 may be utilized to force the members 15 toward or from each other thereby varying the friction between them and the 20 lower end of the goose-neck 14. Also said collars 18 are compressible until they contact or seat upon the ears 11 and 12. Thus the tension exerted by said members 15 on the lower end of the goose-neck 14 is variably 25 adjusted. The position of the goose-neck 14, and parts attached to the upper end thereof with respect to base 10, may be varied at will and the spring tension exerted on the lower end of the goose-neck 14 by the members 15 insures that such goose-neck 14 will 30 be securely held in any position to which the same may have been moved while yet allowing proper adjustment thereof. Further, the position of the socket 26 and bulb 27 may be varied with respect to the goose-neck 14 by use of the wing nut 24 on the threaded screw 23.

Referring to Fig. 5, illustrating a modification of the swivel joint above described, 40 11 and 12 designate the spaced ears and 14 the lower end of the goose-neck 14, while in the holes 13 of the ears and in engagement with the side walls of the goose-neck 14 are metallic washers 29. In said holes 13, 45 and spaced apart from the washers 29 by preferably fibre washers 30, are other metallic washers 31 secured against rotation in the holes 13 by pins 32. Against the outer faces of the ears 11 and 12 are collars 33, the collars 33 and washers 29, 30, and 31 and the 50 lower end of the goose-neck 14 being perforated to receive a shaft 34, this shaft being preferably headed over or riveted to secure the construction just described in assembled position. In this form of swivel joint the adjustment is made at the factory

by a skilled workman, and once made, has been found to last throughout the life of the device thereby rendering unnecessary, and preventing, any tampering with the device 60 by the user.

While I have necessarily shown and described the preferred embodiment of my invention in detail, it is understood that I may vary the details of the construction and 65 arrangement of parts shown within wide limits without departing from the spirit of the invention.

Having thus described my invention, what I claim as new is:

1. In an improved lamp base, the combination of a base, a pair of ears spaced apart from each other and extending upwardly therefrom, alined perforations in said ears, split spring members in said perforations, a goose-neck, a threaded shaft passing through the lower end of the goose-neck and through the split spring members, and means for adjusting the pressure on the split spring members for varying the tension 80 exerted thereby on the goose-neck.

2. In an improved lamp base, the combination of a base, a pair of ears spaced apart from each other and extending upwardly from the base, alined perforations in said ears, split spring members fitting in said perforations, means for preventing rotation of said members in said perforations, a goose-neck, a threaded shaft passing through the lower end of the goose-neck and through the split spring members, and means for adjusting the pressure on the split spring members for varying the tension exerted thereby on the goose-neck.

3. In an improved lamp base, the combination of a base, a pair of ears extending upwardly therefrom and spaced apart from each other and provided with alined perforations whose axes are horizontal, friction members in said perforations, a shaft passing through said friction members, a goose-neck pivotally mounted on said shaft and in engagement on opposite faces with the friction members, a fork formed integral with, and at the upper end of, said goose-neck, a yoke pivotally and adjustably mounted at the extremity of said fork, and a lighting device attached to said yoke.

In testimony whereof, I have signed my name to this specification.

WILLIAM J. SPENCE.
